UNITED STATES PATENT OFFICE.

EDWIN D. SMITH, OF NEW YORK, N. Y.

NECKTIE.

SPECIFICATION forming part of Letters Patent No. 309,659, dated December 23, 1884.

Application filed February 11, 1884. (No model.)

To all whom it may concern:

Be it known that I, EDWIN D. SMITH, of the city, county, and State of New York, have invented certain new and useful Improvements in Neck-Wear, of which the following is a full, clear, and exact description.

The object of my invention is to provide certain new and useful improvements in neck-wear, whereby the construction of the neck-wear will be simplified, the neck-wear will be made stronger and more durable, will not wear off as rapidly as the usual neck-wear, and its beauty will be enhanced.

The invention consists in a shield for neck-wear, made of sheet metal, hard rubber, celluloid, or analogous hard material, and provided on its rear surface with wings for securing the fabric, and a pivoted tongue or latch for locking the shield on the collar-button.

20 The invention further consists in the combination, with the said shield, of ribbons or bands of fabric secured to the same in such a manner as to expose part of the front of the shield.

25 Reference is to be had to the accompanying drawings, forming part of this specification, in which similar letters of reference indicate corresponding parts in all the figures.

Figure 1 is a front view of a cravat provided with my improvement. Fig. 2 is a rear view of the same. Fig. 3 is a cross-sectional elevation of the same. Fig. 4 is a cross-sectional elevation of a modification. Fig. 5 is a rear view of another modification. Fig. 6 is a face view of the metal tongue usually employed in the end of the neckband of a cravat. Figs. 7, 8, 9, 10, 11, 14, and 15 are rear views of different constructions of my improved shield. Fig. 12 is a cross-sectional elevation of the construction shown in Fig. 11. Fig. 13 is an inside perspective view of the shield usually employed in cravats.

40 The ribbon or other fabric, A, of which the cravat is made is folded in the usual manner; but in place of being secured to a shield, A', made of pasteboard and covered with fabric, as has been customary, which shield is shown in Fig. 13, the bands of fabric A are secured to the side wings, B, of a metal shield, C, in 45 such a manner that a triangular or like shaped

part of the face of the shield shows between the upper ends of the bands. The exposed part of the front of the shield is to be enamelled, engraved, plated with gold, silver, or nickel, ornamented with jewels, or ornamented in any other suitable manner. 55

In the middle of the part a a recess, b, is formed, in the base of which an aperture is provided, through which aperture the head d of a collar-button, D, can be passed. The head d will then be held within the recess b, and if the head of the collar-button is ornamented with a precious stone the said precious stone will show in the middle of the exposed part a of the shield C. 65

If desired, the fabric or ribbon A can cover the entire front surface of the shield. To the back of the shield a latch or tongue, E, is pivoted at the upper edge, in which tongue an aperture, E', is formed, from which a shorter slot, E'', extends upward. Preferably the upper part of the tongue is provided with a recess, E''', to receive the head d of the button D. One of the wings B is provided with a projecting pointed prong or tooth, F, which passes into part of the neck-band G, for the purpose of holding the same in place. 75

In place of a pointed tongue, one of the wings B of the shield can be provided with a longitudinal spring-tongue, F', as shown in Fig. 5, under which the end of the band can pass. 80

If desired, the front of the shield can be provided with a plain aperture and need not be recessed, although the recesses enhance the beauty of the shield. 85

In place of the pivoted tongue E made of metal, (shown in Fig. 2,) a tongue, H, made of spring-wire and hung on the back of the shield can be used, as shown in Fig. 5. The collar-button is passed through the spring-loop H' and the loop is pulled downward, thereby causing the shank of the button to pass into a recess, H'', formed in the bottom edge of the back plate of the shield. The upper ends of the loop H' close immediately, and thus hold the button in place. 90

As shown in Figs. 7 and 8, a tongue, E, made of a plate of metal, hard rubber, or analogous material can be combined with a 95

spring-wire loop, H, Fig. 7 showing the outer view, and Fig. 8 the inner view of the said combined tongue. In this case the shank of the button is held between the upper end of the slot E² in the tongue E and the upper ends of the spring-wire loop H'. The tongue E is hinged to the shield at its upper end, and the lower end of the spring-wire tongue H is secured on the lower end of the tongue E.

10 In place of tongues, latches can be used, as shown in Figs. 9 and 10, the latches being pivoted on the back of the shield to swing in the plane parallel with the shield.

As shown in Fig. 9, the latch J is provided 15 at its upper end with a curved prong, J', which passes under the shank of the collar-button and presses the shank against the upper end of the slot J² in the back of the shield. The latch J is provided with a hook-prong, K, 20 adapted to catch on the outer edge of one of the wings B of the shield, for the purpose of holding the latch in place. In place of the latch J a latch, L, (shown in Fig. 10,) can be used, which is provided with an aperture, L', 25 from which a curved slot, L², extends upward.

This latch hangs vertically and is locked in position automatically and by its own weight, the collar-button shank being held in the upper end of the slot J² in the shield, and in the 30 upper end of the curved slot L² of the latch.

If desired, the tongue or the latch can be dispensed with. In this case the back of the shield is provided with the aperture M, from which a slot, M', extends upward, the front and back 35 plates of the shield being provided with recesses, as shown in Figs. 11 and 12. In this case the head of the button is passed through the aperture M and then the shield is drawn downward to cause the shank to pass through 40 the slot M' until the head passes into the recesses.

In the construction shown in Fig. 15 the shield is provided with only the two wings B, and with a slot, O, extending down from the 45 upper edge and having its lower end within a recess, O', in the front of the shield. In this case the shank of the button passes down through the slot from the upper edge of the shield and the cravat is held in place on the 50 neck and on the collar-button by means of the band G only. In Fig. 14 a similar construction is shown, in which the shield is provided with a simple aperture, P, through which the head of the button passes. In all cases the 55 shield is provided with the two wings B for securing the fabric, band, or ribbon of which the cravat is made. The upper edge of the shield is not covered with fabric, and this is one of the great advantages of my improved 60 cravats and other neck-wear, for the beard wears off the upper edges of the cover of the usual shield. I have replaced the curved upper edge by a metal edge which cannot be worn off. As the lower parts of a cravat do 65 not wear off, a cravat provided with my improved shield will wear longer than other cravats. Besides this, the pasteboard or other

like shields used in cravats heretofore bend and break easily and lose their stiffness, whereas my improved shield always retains its stiffness.

70 By means of the latches and tongues a shield can be held securely on the collar-button, and the neckband G can be dispensed with, or need only be used as an ornament.

75 The tongue shown in Fig. 6, which has usually been placed in the end of the neckband of a cravat, can be dispensed with, as in my improved cravat the end of the band need not be forced in between the shield and the fabric held on the front of the same, and therefore the end of the band need not be stiffened.

80 A cravat provided with my improved shield can be fastened more readily than the usual cravats, as all that is necessary is to pass the head of the button through the aperture in the tongue and then pull the cravat downward and press it toward the collar-button, so that the head of the collar-button will project through the aperture in the front of the 85 shield.

85 I have described the shield as being made of metal; but it can be made of hard rubber, celluloid, or analogous hard material.

90 The above-described shield can also be secured to cravats or bows already made, and can be secured to bows of different kinds.

95 If desired, the shield can be covered with silk, but must still be provided with the aperture for the head of the collar-button.

100 Having thus described my invention, what I claim as new, and desire to secure by Letters Patent, is—

1. A shield for neck-wear, consisting of a plate provided with wings for fastening the 105 fabric, and of a pivoted tongue or latch for locking the shield on the collar-button, substantially as herein shown and described.

2. The combination, with a metal shield for neck-wear, of a tongue pivoted to the rear of the same at the upper edge, and provided with an aperture from which a slot extends upward, substantially as herein shown and described.

3. In a cravat or other neck-wear, the combination, with a shield made of metal, hard rubber, or an analogous hard substance, of a fabric, band, or ribbon secured to the said shield in such a manner as to expose to view 115 part of the face of the said shield, substantially as herein shown and described.

4. In neck-wear, the combination, with a shield made of metal, rubber, or analogous hard material, and having an aperture for the head of the collar-button, of bands of fabric 120 or ribbons held on the same in such a manner that part of the face of the shield around the aperture will be exposed to view, substantially as herein shown and described.

EDWIN D. SMITH.
